UNITED STATES PATENT OFFICE

VINCENT V. VEENSCHOTEN, OF ERIE, PENNSYLVANIA

SPRAY NOZZLE

Application filed October 17, 1930. Serial No. 489,389.

The present invention is designed to improve and simplify spray nozzles. With such nozzles it is desirable to deflect the spray laterally and in many locations control the spray so that its flow will be comparatively low, thus protecting windows and other walls adjacent to where the spray is in use. It is also desirable to have this adjustable so that the deflection of the spray may be adjusted 5 in a manner to adapt it for the location in use, and where the adjustment is accomplished by a screw to have means provided whereby the frictional engagement of the screw may be made such as to assure the 10 maintenance of the adjustment. It is also desirable to offer as little resistance to the flow of water through the nozzle as possible. The present invention is designed to provide a spray nozzle capable of carrying out the 15 above suggestions in a practical manner. Features and details of the invention will appear from the specification and claims.

A preferred embodiment of the invention is illustrated in the accompanying drawing 20 as follows:—

Fig. 1 shows a central vertical section of the nozzle.

Fig. 2 a section on the line 2—2 in Fig. 1.

1 marks the body of the nozzle. This has 25 an interior screw thread 2 by means of which the nozzle is attached to a fitting 3 carried by a support 4.

The upper end of the body has a smooth 30 wall 5 and a spreading member 6 has an exterior wall fitting the wall 5 and a screw thread 7 at its lower end fitting the screw 35 thread 2. The member has an opening 6a extending through its bottom end into which the water passes in going through the body.

40 It is provided with a slit 8 by means of which the lower end of the member may be slightly expanded if desired and this makes a spring fit of the screw at the lower end of the member and assures such frictional engagement

with the screw 2 as to lock the spreading member in adjustment in the body.

The spreading member is provided with a deflecting head 9 having the inclined, or deflecting surface 10 around its under edge. 50 The member has radially disposed slots 11 which extend from the central opening 6a through the wall of the member. The upper ends of the slots are curved and upwardly inclined at 12. The slots are preferably 55 formed by a milling operation which makes a curved cut in the exterior surface and thus affords this inclination. These slots are also slightly expanding toward the outer surface so as to aid in the spreading of the spray. 60

With this structure it will be seen that there is very little obstruction to the water, there being a free open passage through the spraying member and that the radially disposed, or deflecting openings with the deflecting head while they do break the water into a spray and deflect it still accomplish this with as little resistance as possible. Further the construction as a whole is very simple 65 in that the same screw thread which operates for the fitting also accords means for connecting the spreading member with the body. 70

What I claim as new is:—

1. In a spray nozzle, the combination of a body having a screw thread therein; and a spreading member screwed into the body, said member having a deflecting head, a central opening below the head and extending through the bottom of the member, and radially disposed openings extending through 80 the wall of the member below the head and above the body, the head being adapted to spread jets issuing from the openings. 75

2. In a spray nozzle, the combination of a body having a screw thread therein; and a spreading member screwed into the body, said member having a deflecting head, a central opening below the head and extending through the bottom of the member, and radially disposed openings extending through 90

the wall of the member below the head and above the body, the head being adapted to spread jets issuing from the openings, the upper ends of the radially disposed openings 5 being upwardly inclined.

3. In a spray nozzle, the combination of a body having a screw thread therein; and a spreading member screwed into the body, said member having a deflecting head, a central 10 opening below the head and extending through the bottom of the member, and radially disposed openings extending through the wall of the member below the head and above the body, the head being adapted to 15 spread jets issuing from the openings, the spray openings flaring toward the outside.

4. In a spray nozzle, the combination of a body having a screw thread therein; and a spreading member screwed into the body, said 20 member having a deflecting head, a central opening below the head and extending through the bottom of the member, and radially disposed openings extending through the wall of the member below the head and above the body, the head being adapted to 25 spread jets issuing from the openings, the spray openings flaring toward the outside and the upper ends of the openings being upwardly inclined.

5. In a spray nozzle, the combination of a body having a screw thread therein; and a spreading member screwed into the body, said member having a deflecting head, a central opening below the head and extending 30 through the bottom of the member, and radially disposed openings extending through the wall of the member below the head and above the body, the head being adapted to 35 spread jets issuing from the openings, said member being adjustable through its screw connection with the body to vary the openings.

6. In a spray nozzle, the combination of a body having a screw thread therein; and a spreading member screwed into the body, said member having a deflecting head, a central opening below the head and extending 40 through the bottom of the member, and radially disposed openings extending through the wall of the member below the head and above the body, the head being adapted to 45 spread jets issuing from the openings, said member being adjustable through its screw connection with the body to vary the openings, the wall of the spreading member being 50 axially slotted to permit the expansion of the screw.

7. In a spray nozzle, the combination of a body having a screw thread therein extending 55 from the bottom to adjacent the top, said screw thread at the bottom being adapted to attach the body to a fitting and said body having a cylindrical wall adjacent to the top; and a spreading member screwed into the 60 screw threads of said body, said member hav-

ing a cylindrical surface fitting the cylindrical surface at the upper end of the body and having a deflecting head, a central opening below the head and extending through the bottom of the member, and radially disposed openings through the wall of the member below the head and above the body, the head being adapted to spread jets issuing from the openings. 70

In testimony whereof I have hereunto set 75 my hand.

VINCENT V. VEENSCHOTEN.
